UNITED STATES PATENT OFFICE.

FRANK J. ANDEL, OF CLEVELAND, OHIO.

WHEEL REMOVER.

Application filed December 24, 1926. Serial No. 156,807.

My invention relates to an improvement in wheel removers, my general object being to provide a simple device which may be easily affixed to the screw-threaded extremity of an 5 axle spindle and utilized to transmit sharp blows to the spindle without injury to the screw-threads, thereby jarring the wheel loose on the spindle.

In the accompanying drawings, Fig. 1 is 10 a sectional view of a wheel hub sleeved upon an axle spindle and a sectional view of my improved wheel remover affixed to the screw-threaded spindle extension. Fig. 2 is a cross section of the wheel remover. Fig. 3 is a sectional view, and Fig. 4 an end view thereof. Fig. 5 is a perspective view of the device.

In certain types of automobiles the wheel hubs are wedged tightly upon tapered spindles and therefore difficult to remove 20 after protracted use. The spindle 2 has a reduced extension 3 which is screw-threaded to receive a nut. A common practice is to remove the nut and strike the end of the extension with a hammer to jar the wheel loose 25 on the spindle. Such treatment batters and upsets the end of extension 3 and injures the screw-threads, especially the lead-in thread.

Assuming that that is the condition of the 30 spindle extension with a wheel —W— tightly wedged upon the spindle, I provide a simple device for jarring the wheel loose without injury, and in so doing correct the previous injury to the screw-thread. This device comprising a cylindrical body 4 has a 35 relatively long axial bore 5 in its outer end, a central chamber 6, and a screw-threaded opening 7 in its inner end. The mouth 8 of opening 7 is of flaring shape and this end of body 4 is slotted at a number of places 40 tangentially in respect to the inner circle defined by the lands of the screw-threads of opening 7. The slots provide a series of sharp cutting edges 10 at the beginning of the screw-thread in the flaring mouth or entrance 45 8 which permits easy attachment of cylinder 4 to extension 3 regardless of a mutilated screw-thread thereon. So connected cylinder 4 provides a tubular extension for the spindle adapted to support and guide a loose plunger 50 11 in its longer and smaller bore 5 axially coincident with the axle spindle. Plunger 11 is provided with a flat round head 12 loosely seated within central chamber 6 which pre-

vents the plunger from slipping outwardly. The flat end of head 12 abuts the end of screw-threaded extension 3, and the opposite end of the plunger carries a cap or collar 14 which is spaced apart from the outer end 15 of cylinder 4 when the cylinder is screwed upon spindle extension 3. A hexagonal enlargement 16 is 55 provided for wrench engagement of the cylinder, but the cylinder may be hexagonal its full length if desired. Cylinder 4 is screwed only a short distance upon the spindle extension to permit head 12 to have loose play with in chamber 6, as cylinder 4 functions only as a fixed guide and support for the plunger in wheel removing operations. Thus when the device is affixed to the spindle as explained, plunger 11 is supported in a floating position 60 axially opposite the end of the axle spindle and the operator is enabled to strike the exposed cap 14 on the plunger without danger of mutilating or stripping the screw-threads. Thus with the present device it is not necessary for the operator to exercise caution in attaching the cylinder to the spindle as it 65 may be screwed only part way and still serve to hold and guide the plunger properly. Cap or collar 14 is a separate piece of hard 70 metal which is secured tightly upon the outer end of plunger 11 in any suitable way, for example, by shrinking or clamping it thereon. This cap or collar serves several purposes;—it provides a replaceable enlargement 75 adapted to receive the blow of a hammer; it limits the movement of the plunger in one direction; and it co-acts with head 12 in locking the plunger loosely within cylinder 4 so that the plunger and cylinder cannot be separated 80 accidentally.

What I claim is:

A wheel remover, comprising a device having a screw-threaded opening formed with a flaring mouth and cutting edges adapted to be 85 readily screwed upon a mutilated screw-threaded wheel spindle, and a loose striking plunger extending through said device to the base of said opening, said plunger having a head loosely confined within said opening and adapted to abut against the end of said spindle, and a separate locking collar affixed to the outer end of said plunger in spaced 90 relation to the outer end of said device.

In testimony whereof I affix my signature.
FRANK J. ANDEL.
